INVENTOR
DAVID JOHN DAVIS
By *John Davis* Atty

UNITED STATES PATENT OFFICE.

DAVID JOHN DAVIS, OF HAVERFORDWEST, WALES.

PERMUTATION-LOCK.

1,329,041.

Specification of Letters Patent. Patented Jan. 27, 1920.

Application filed April 12, 1917. Serial No. 161,624.

To all whom it may concern:

Be it known that I, DAVID JOHN DAVIS, a subject of His Majesty the King of England, and resident of Haverfordwest, South 5 Wales, Kingdom of England, have invented certain new and useful Improvements in and Relating to Permutation-Locks, of which the following is a specification.

This invention relates to improvements 10 in permutation locks, and has for its primary object to provide an improved device of this character particularly adapted for fastening and securing boxes, traveling trunks, attaché cases, letter cases, handbags, 15 and the like.

Another object of the invention is to provide a code or permutation lock in which the parts are few in number, are of simple, durable and improved construction, and are 20 efficient in operation.

The invention will now be described with reference to the drawings forming a part of this specification, in which drawings:—

Figure 1 is a front elevation of a suitable 25 construction of the complete permutation lock;

Fig. 2 is a side elevation of the permutation lock;

Fig. 3 shows the hasp in side elevation 30 and a cross sectional elevation of the lock proper on the line 3—3 of Fig. 1;

Fig. 4 is a front elevation of the lock without the hasp;

Fig. 5 shows cross sections of the ad- 35 justable disks and the front and back plates detached from one another; and

Fig. 6 illustrates separate elevations of the three adjustable disks in the correlated 40 positions they occupy when the hasp is free to be inserted or withdrawn.

The lock or fastening device illustrated 45 comprises three flat circular locking disks *a*, *b* and *c* each adapted to rotate independently of the others, and each provided with a notch or keyway *d*. The disk *a* is formed with a sleeve *e* upon which the disk *b* is mounted, and the disk *b* with a sleeve *f* on which the disk *c* is mounted, while the disk *c* has no projecting forma- 50 tion on its back face, and each disk is provided with a pointer or projection *g* on its periphery for a purpose hereinafter referred to.

The three disks are arranged between a 55 front flat circular rigid or non-rotary plate *h* and a back rigid or non-rotary plate *i*,

and are mounted on a boss *j*, formed on the rear face of said front plate. The boss serves as a pivot on which disks rotate directly or indirectly and on which they are 60 held in position in their respective order. The boss *j* is formed with a shank *k* which after the locking disks have been placed together in their respective positions, is passed through a hole *l* provided in the back plate 65 and hammered over to rigidly secure the front plate to said back plate. Each of the front and back plates is formed with a slot or keyway *m* and the boss *j* is cut away at *n* to allow for the free passage of a locking pin having a rearwardly extending portion *o* and an upturned portion *p*, said locking pin being provided on a hasp *q* pivoted at *r* to a plate *s*. The plates *h* and *i* constitute in effect a case. The edges of the 70 locking disks are exposed and the projections *g* extending beyond the edge of the front plate *h* serve as operating means to be engaged when rotating the disks to bring their keyways into or out of alinement. 75

It is to be understood that suitable letters, marks, or other indicia well known in the art of permutation locks, will be provided to coöperate with the pointers *g* of the rotatable locking disks to enable the 80 alining of the keyways when it is required to pass the locking pin *o*—*p* therethrough. The indicia may appear on the case in any desired relative position.

The back plate *i* may be of any shape 85 and size, and is secured in suitable manner to a box case or the like, represented by dotted lines at *u*, Figs. 1, 2, and 3, such as by screws, nails, or the like, while the plate *s* is similarly secured to the lid *v* of the 90 box, case or the like.

The action of the lock or fastening device is as follows:—The lock is unfastened or opened when all of the notches *d* and the slots *m* are collinear thus allowing the locking pin *o*, *p* to be pressed in or withdrawn 100 easily. To lock or fasten the device the hasp *q* is shut down and the locking pin *o*, *p* thereon inserted through the notches in the disks and seated within the slots in 105 the plates. If now, the disks are rotated in either direction, to move their notches out of alinement with the slots *m*, the pin *o*, *p* is firmly locked in position with its upstanding portion *p* disposed behind the 110 disks and within the slot *m* of the back plate *i*, and cannot be withdrawn until the

notches and slots are again collinear. To disengage the locking pin and unfasten the hasp *q* the locking disks have to be rotated in such manner that their notches are collinear with one another and with the slots in the plates *h* and *i*, and for this purpose the points *g* on the disks must each be brought exactly in line with a particular letter, number or index of the case. The combination of such letters, numbers, or other marks serves as the secret key code of that one and particular lock, and it is obvious that each lock will have a secret combination of its own. The combination may be further complicated by the addition of one or more locking disks, only three being shown in the drawings.

It will be seen by referring to the drawings that the locking pin *o*, *p* of the hasp 20 passes through the disks and plates and the notches and slots therein in a plane disposed to one side of the axis of the disks, and when in its fastening or closed position and when the disks are in locking position, 25 is located and extends through and within the disks and plates, Fig. 3.

What I claim is:—

A lock comprising a back plate provided with attaching means and having a central 30 opening, said back plate being also provided

with a slot at one side of the opening between the same and the periphery of the back plate, a front plate of circular form having a slot in register with the slot of the back plate and provided with a central boss 35 on its rear face bearing against the back plate and having a groove in alinement with the said slots, said boss being also provided with a shank projecting through the opening of the back plate and rigidly connecting the front and back plates which are spaced by the said boss, and a plurality of lock disks rotatably mounted one upon the other and upon the said boss between the front and back plates and provided with 40 slots located within the peripheries of the lock disks and adapted to register with one another and with the slots of the front and back plates, said disks being exposed at the periphery of the front plate for manipulation, and a co-acting hasp member having a substantially hook-shaped portion movable through the said slots when the same are in register and lying in said groove and the slot of the back plate when in locked 45 position.

In testimony whereof I have hereunto signed my name.

DAVID JOHN DAVIS.
